UNITED STATES PATENT OFFICE.

EMIL L. SCHNEPF, OF TRENTON, NEW JERSEY, ASSIGNOR TO SCAMMELL CHINA CO., OF TRENTON, NEW JERSEY.

DESIGN FOR A PLATE.

Application filed November 23, 1926. Serial No. 19,824. Term of patent 14 years.

To all whom it may concern:

Be it known that I, EMIL L. SCHNEPF, a citizen of the United States, residing at Trenton, in the county of Mercer and State of New Jersey, have invented a new, original, and ornamental Design for Plates, of which the following is a specification, reference being had to the accompanying drawing forming part thereof.

The figure is a plan view of a plate show-

ing my new design only a portion of the ornamentation being shown, it being understood that the ornamentation shown on the half of the plate illustrated is continued around the border of the entire plate in an identical manner with what is shown.

I claim:

The ornamental design for a plate, as shown and described.

EMIL L. SCHNEPF.
